UNITED STATES PATENT OFFICE.

ROY LOFFLAND, OF WORTHINGTON, INDIANA, ASSIGNOR TO CEMENT PRODUCTS COMPANY, OF WORTHINGTON, INDIANA, A CORPORATION OF INDIANA.

SILO-DOOR MOUNTING.

1,282,605.

Specification of Letters Patent. Patented Oct. 22, 1918.

Application filed April 23, 1917. Serial No. 163,888.

To all whom it may concern:

Be it known that I, Roy Loffland, a citizen of the United States, residing at Worthington, in the county of Greene and State of Indiana, have invented certain new and useful Improvements in Silo-Door Mountings, of which the following is a specification, reference being had therein to the accompanying drawing.

10 This invention relates to certain new and useful improvements in silo door mountings, the object being to provide a door mounting which is so constructed that the door is adjustably supported in a rigid manner so as 15 to prevent the same from sagging.

Another object of my invention is to provide a door mounting in which the door is pivotally and adjustably supported on pivoted arms in order to enable the same to be 20 adjusted so as to obtain an accurate fit when in closed position within the door frame.

Another object of my invention is to provide a novel form of supporting members adapted to receive hangers carried by the 25 door in such a manner that the door is free to swing on the supports and the supports on the pivoted arms in order to obtain a universal movement.

Another and further object of my invention 30 is to provide a door mounting composed of a pair of pivoted arms connected together by braces having curved ends in order to enable the pivotally mounted door carried by the free ends of said arms to be swung into 35 the silo against the inner face of the wall thereof so as not to obstruct the filling of the silo.

Other and further objects and advantages 40 of the invention will be hereinafter set forth and the novel features thereof defined by the appended claims.

In the drawings,

Figure 1 is a front view of a portion of the silo showing the application of my improved 45 construction of door mounting;

Fig. 2 is a horizontal section showing the door in closed position taken on lines 2—2 of Fig. 1;

Fig. 3 is a similar view showing the door 50 in open position; and

Fig. 4 is a perspective view of my improved construction of door mounting showing the parts separated.

Like numerals of reference refer to like 55 parts in the several figures of the drawing.

In the drawing I have shown my improved construction of door mounting applied to a silo and door formed of plastic material in which 1 indicates the wall of the silo, 2 a series of superposed door frames 60 which are provided with rabbeted edges as shown at 3 into which is adapted to fit the rabbeted edges 4 of a plastic door 5, it of course, being understood that a door is provided for each door frame and each frame 65 and door is constructed exactly like each other frame and door.

Embedded within the walls of one of the side pintles of the door frame is a vertically disposed reinforcing element 6 in the form 70 of a flat bar having angled apertured ends 7' projecting out beyond the face of the door frame forming horizontally disposed bearings on which are mounted the apertured pivot portions 7 of arms 8, said pivot 75 portions being held on the bearings 7' of the elements 6 by a vertically disposed pinte 9. The arms 8 are provided with curved portions 10, the pivot portions 7 being formed by twisting the ends of the strips from which 80 the arms are formed, and these arms are connected together by braces 11 in order to produce a substantial frame, the arms forming rounds so as to provide a ladder for the silo or other structure. 85

The free ends of the arms 8 are twisted to provide horizontally disposed bearing portions 12 which are provided with apertures in which are pivotally mounted the sprockets 13 of supports 14 adapted to turn on the 90 bearings 12 as will be hereinafter fully described.

The supports 14 are bifurcated as shown at 15 adapted to receive the U-shaped hangers 16 carried by the door 5, said hangers 95 being provided with right angled ends 17 adapted to be embedded within the plastic door while being molded so as to securely anchor the hangers within the door. One of the furcations of the bifurcated support 14 100 is provided with a threaded bore 18 adapted to receive a set screw 19 which is pointed and is provided with a concaved end 20 adapted to engage the U-shaped hanger 16 so as to lock the hanger in adjusted position within the support 14. 105

The hangers 16 are preferably formed of wrought iron in order to enable the same to be bent slightly in order to obtain a slight adjustment, and by adjusting these hangers 110

within the pivotally mounted supports carried by the arms, the doors can be adjusted in respect to the door frames so as to obtain an accurate fit when in closed position. The 5 curved portions 10 of the arms allow the door to be swung into and against the inner face of the silo.

The doors are held in closed position by locking bars 21 pivotally mounted on the 10 doors.

From the foregoing description it will be seen that I have provided a silo door mounting in which a frame formed of a pair of pivotally mounted arms connected together 15 by braces is pivotally mounted on bearings carried by the door frame, and is provided with spaced bearings on which are pivotally mounted supports in which are adjustably mounted hangers carried by the door, where- 20 by I am able to support a door weighing from seventy-five to one hundred and twenty-five pounds in a rigid manner so that the door when in closed position will fit accurately within the door frame in order to 25 form a tight closure which is essential in a silo door.

I claim:

1. The combination with a structure having a door frame and a pair of arms pivotally carried by said door frame, vertical supports pivotally mounted upon said arms, a door having substantially U-shaped hangers slidably mounted in said supports, and means for locking said hangers in adjusted 35 position within said supports.

2. The combination with a silo having a door frame and a door therefor, of a reinforcing element embedded within the door frame having angled ends forming bearings, arms 40 pivotally mounted on said bearings, braces connecting said arms, said arms being provided with bearings at their free ends, bifurcated supports pivotally mounted upon said bearings, U-shaped hangers carried by said 45 door mounted within said supports, and means for locking said hangers in adjusted position within said supports.

3. The combination with a silo having a door frame and a door therefor, of a bar em-

bedded within the door frame having an- 50 gled apertured ends forming bearings, arms provided with apertured pivot portions mounted upon said bearings, a pintle pin extending through said bearings and pivot portion, means connecting said arms, said 55 arms having horizontally disposed apertured bearings at their free ends, supports provided with pivots mounted in the apertured bearings of said arms, U-shaped hangers carried by said door, laterally adjustably 60 mounted within said supports, and set screws carried by said supports engaging said hangers for locking said hangers in adjusted position within said supports.

4. The combination with a silo having a 65 door frame and a door therefor, formed of plastic material, of a pair of arms pivotally supported by said door frame, braces connecting said arms, said arms being provided with horizontally disposed apertured 70 bearings at their free ends, supports mounted on said bearings having pintles extending into the apertures thereof, said supports being provided with bifurcated portions, hangers carried by the door mounted for 75 lateral adjustment within the bifurcated portions of said supports, and set screws having cup-shaped ends mounted in said supports engaging said hangers for holding 80 said hangers in adjusted position within said supports.

5. A silo door mounting comprising a pivotally mounted frame having bearings at its free end, vertical supports pivotally mounted 85 on said bearings, door hangers having horizontally disposed portions arranged parallel with the face of the door slidably mounted within said supports for lateral adjustment and means for locking said 90 hangers in adjusted position within said supports.

In testimony whereof I hereunto affix my signature in the presence of two witnesses.

ROY LOFFLAND.
